UNITED STATES PATENT OFFICE.

WALTER L. RICE, OF DENVER, COLORADO.

CANOPY FOR OPEN-WINDOW SLEEPING-BEDS.

1,088,726.

Specification of Letters Patent. Patented Mar. 3, 1914.

Application filed June 17, 1912. Serial No. 704,115.

To all whom it may concern:

Be it known that I, WALTER L. RICE, a citizen of the United States of America, residing in the city and county of Denver and State of Colorado, have invented a new and useful Canopy for Open-Window Sleeping-Beds, of which the following is a specification.

My invention relates to improvements in canopies for open window sleeping beds; and the objects of my invention are: first, to provide as near absolutely open air sleeping conditions in bed-rooms as it is possible to get, and to provide means for inclosing the bed in a folding canopy in such a manner as to prevent drafts of air from flowing over the bed and its occupant. And second, to provide a folding canopy for a bed and window, by which a bed can be placed close to an open window in bed rooms, and be inclosed by the canopy in such a manner as to receive the full inflow of the outside atmosphere, and be free from air drafts across the bed. I attain these objects by the mechanism illustrated in the accompanying drawings, in which:

Figure 1, is a sectional view, showing a bed arranged in proximity to a window, and a folding canopy embodying my invention hinged to the bed in such manner as to inclose the bed while its end adjoining the window is open. Fig. 2, is a plan view of Fig. 1. Fig. 3, is an end elevation of Figs. 1 and 2, looking toward the end of the bed and the window. Fig. 4, is a vertical sectional view showing both the bed and canopy folded back into the cabinet in a position of disuse. Fig. 5, is a fragmental side view on an enlarged scale showing the manner in which the canopy bows are pivotally connected. Fig. 6, is a plan view of the same. And Fig. 7, is an end view thereof.

Similar letters of reference refer to similar parts throughout the several views.

Referring to the drawings: The numeral 1 designates a bed which may be of any suitable type, kind, or character; 2 designates a window opening in the wall of a building; and 3 designates a bed room in which the window and bed are located.

My improved canopy is preferably shown in connection with an ordinary folding bed, supported by hinge arms 4, which are pivoted at their lower ends to angle plates 5, or other suitable means, secured to the floor, while their upper ends are pivotally at-

tached at suitable points to the sides of the bed. The same bolts which secure the upper ends of the arms 4 to the bed, also secure the lower ends, of slotted arms 6, which are slidably mounted on bolts 7, which enter the sides of a casing of cabinet 8, which inclose the bed when folded, and which is of a type in common use. Upon the upper edge of each side of the bed, adjacent to its head end, are secured hinge plates 9, these plates being so positioned that their hinge ends are on a line with the inner face of the frame which forms the front of the cabinet through which the bed passes as it is folded and unfolded, as will be understood by reference to Figs. 1 and 3. To the hinge plates 9 are pivotally secured the extremities of the lower yoke shaped bow 10, which constitutes one of the canopy supports. This bow is of such a length that its end member rests upon and lies parallel with the foot board of the bed when the canopy is in position for use, as shown by Fig. 1. Adjacent to the extremities of this bow, are formed pairs of upwardly projecting apertured ears 11, between which are pivotally secured the L-shaped extremities 12 of a second bow 13, as clearly shown in Fig. 5, the heels of said extremities being apertured for this purpose and lie between and are connected to the ears 11 by pins 14, while the outer ends of the L's are bifurcated and are apertured and have pivotally secured between them, the ends of a third bow 15, also having L-shaped extremities 16, to the outer bifurcated ends of which are pivotally secured a fourth bow 17, having similar extremities 18, to the outer bifurcated ends of which are connected the straight extremities of the fifth and last bow 19. All of the L-shaped extremities of the several bows, are bifurcated at their outer ends, so that the heels of the L-shaped extremities of one bow are pivotally secured between the bifurcated ends of the preceding bow, as will be fully understood by reference to Figs. 5, 6 and 7. These bows are all of the same length from their pivotal points outward, and upon the bows is secured a canopy 21 of any suitable flexible material such as is commonly employed for carriage tops, this material being adapted to fold in between the bows, as in the case of an ordinary buggy or carriage top, when the canopy is in a position of disuse, as shown in Fig. 4. By forming the bows with L-shaped extremities and connecting them in the manner

shown, a sufficient space is formed between their pivoted ends to permit the canopy to fold in between them without being crumpled.

While I have illustrated metal bows, they could obviously be made of wood with metal L-shaped hinge members secured to their extremities, the invention contemplating bows of any suitable material.

When the bed and canopy are in a position of use, as shown by Fig. 1, the upper portion of the bow 19, rests against the inner face of the front of the cabinet, and is held thereby against outward movement, and the arc of the canopy is such that when the bow 10 rests upon the bed, the canopy will be taut, and as the bow 10 rests squarely upon the sides and foot boards of the bed, and the bow 19 rests squarely against the inner face of the front of the cabinet surrounding the bed-receiving opening therein, the occupant of the bed receives the full benefit of the fresh air, without danger from drafts of air, which would otherwise result. When not in use, the bed with the canopy may be folded or swung into the cabinet, as shown in Fig. 4, or if desired, the bed may remain in a horizontal position, and the canopy may be folded back against the window frame, as shown by dotted lines in Fig. 1. When thus arranged, the window may be opened to admit air to the room, and the light from the window will be only partially cut off. A board 20, is placed between the sides of the window frame, at the upper end of the cabinet, and so as to extend to the window sash, as shown. This board closes the opening at this point, and cuts off air drafts, as will be understood by reference to Fig. 1.

In operation, the bed is let down—where a folding bed is employed—and the occupant unfolds the canopy from its position of disuse, as shown by dotted lines, Fig. 1, to the position shown in full lines, by drawing on the outer bow 10, until it rests upon the sides and foot of the bed, the bow 19 being engaged by the front of the cabinet. The lower window sash is then raised, and the occupant of the bed receives the full benefit of the fresh air, without the harmful effects of air drafts, which are entirely cut off by the arrangement of the canopy, and the manner of its connection with the bed and cabinet.

Having described my invention, what I claim as new and desire to secure by Letters Patent, is:

1. In an attachment for beds as specified, the combination with a cabinet adapted to surround the lower portion of a window and having an open front and back, and a bed, one end of which extends into said cabinet, of a canopy comprising a plurality of bows hinged together at their extremities and being radially disposed when in a position for

use, and a fabric covering secured to said bows to form a housing, the first of said bows being pivotally attached to the sides of the bed, while the last bow is adapted to rest against the inner face of the front of the cabinet surrounding the opening therein.

2. In an attachment for beds as specified, the combination with a cabinet open in front and back, and a bed, one end of which extends into said cabinet near its lower end, of a plurality of radially disposed bows hinged together at their lower ends, the first bow being pivoted at its extremities to the sides of the bed and adapted to rest upon the sides and foot board of said bed, while the last bow rests against the inner face of the front of the cabinet surrounding the opening therein, and a fabric housing secured upon said bows.

3. In an attachment for beds as specified, the combination with a vertically disposed cabinet which is open front and back, and a bed, one end of which extends into the lower portion of the cabinet, of a collapsible canopy pivotally attached to opposite sides of the bed, and forming a housing which extends from the foot of the bed to the top of the opening in the cabinet, and adapted to be collapsed and swung back into said cabinet when not in use.

4. In an open window canopy for beds, the combination with a cabinet adapted to inclose the lower portion of the window, and a bed extending into the cabinet, the cabinet being open front and back, of a collapsible canopy comprising a plurality of radially disposed bows pivotally connected at their ends, the first of said bows being horizontally disposed and hinged at its ends to the sides of the bed, while the last of said bows is vertically disposed and rests against the inner face of the front of the cabinet surrounding the opening therein, and a fabric housing surrounding said bows, said canopy being adapted to be folded back into the cabinet when not in use.

5. In an open window canopy for beds, the combination with a bed and an open ended cabinet surrounding one end of the bed and extending above the same, of a collapsible arc-shaped housing extending from the opening in the cabinet and resting upon the sides and one end of the bed, said housing being pivotally secured to the sides of the bed in line with the front of the cabinet, and being adapted to be collapsed and swung into the cabinet, when not in use.

6. In an open window canopy for beds, the combination with a bed, of an inverted U-shaped frame for housing one end thereof and the lower portion of a window, and a collapsible arc-shaped canopy extending into the frame, and resting upon the sides and one end of the bed, and hinged to the opposite sides of the bed at the apex of the angle.

formed by the junction of the horizontal and vertical portions of said canopy.

7. In an open window canopy for beds, the combination with a cabinet open back and front, and adapted to surround the lower portion of a window, and a bed hinged to fold into said cabinet, of a canopy for said bed, comprising U-shaped bows, radially disposed and hinged together at their ends, and a fabric covering for said bows, the lower end bow being horizontally disposed, when in a position of use, and adapted to rest upon the sides and one end of the bed, and being hinged at its ends to the sides of the bed on a line with the front of the cabinet, while the opposite end bow is vertically disposed, and is adapted to rest against the inner face of the cabinet surrounding the opening therein.
- 10 8. In an open window canopy for beds, the combination with a cabinet open front

and back and adapted to surround the lower portion of a window, and a bed hinged to fold into said cabinet, of a canopy for said bed, comprising a plurality of U-shaped bows, pivotally connected at their ends, the bottom bow being hinged at its end to the sides of the bed on a line with the front of the cabinet, and adapted to rest on the bed, while the last of the bows is vertically disposed and rests against the inner face of the cabinet surrounding the opening therein, and a fabric cover inclosing the bows, the said canopy being adapted when in use to form a housing above the bed which opens into the cabinet.

In testimony whereof I affix my signature in presence of two witnesses.
